UNITED STATES PATENT OFFICE.

RICHARD N. OAKMAN, JR., OF GREENFIELD, MASSACHUSETTS, ASSIGNOR
TO THE A. F. TOWLE & SON COMPANY, OF SAME PLACE.

DESIGN FOR A SPOON OR FORK HANDLE.

SPECIFICATION forming part of Design No. 22,502, dated June 6, 1893.

Application filed April 3, 1893. Serial No. 468,941. Term of patent 7 years.

To all whom it may concern:

Be it known that I, RICHARD N. OAKMAN, Jr., a citizen of the United States, residing at Greenfield, in the county of Franklin and State of Massachusetts, have invented and produced a new and original Design for a Spoon or Fork Handle, of which the following is a specification, reference being had to the accompanying drawings, which form a part of the same.

This invention relates to a design formed upon the handle of a spoon, fork, or similar article; and it consists in an ornamental configuration, herein shown and claimed.

Figure 1 of the accompanying drawings represents a front view of a spoon or a fork, as indicated by dotted lines containing my ornamental design. Fig. 2 represents a side or edge view thereof.

The ornamental configuration constituting my design is applied to the front or face of the handle of a spoon, or fork as indicated by dotted lines, or similar article. The outline of the handle extends for a short distance in slightly converging lines from the base thereof and then in long diverging and slightly curved lines to the upper part of the handle. Following the outline on each side is a raised bead, *a*, extending from the base up to two small lateral knobs, *e*. Within this bead, *a*, and extending from the base to about

the middle of the length of the handle there is formed a surface filling of wavy or serpentine stem and leaf work, *b*, having numerous lateral and terminal points, as shown. At 35 the end of the stem and leaf work, *b*, two inner beads, *a'*, extend to the knobs, *e*. The tip, *f*, of the handle is given a configuration resembling three leaves caught together at their stems, the middle leaf being shown in 40 full plan while the lateral leaves curve downward on each side and form the outline of the tip and terminate at their ends in small outwardly turned projections, *i*, *i*, which rest upon the inwardly curved or scroll like stems 45 of the leaf work, *c*, *c*, on each side of the handle. The leaves, *c*, swell outward on each side below the knobs, *i*, *i*, and then curve downward and inward to the terminal knobs, *e*, *e*, as shown. The lateral leaves, *c*, *c*, have 50 also numerous inwardly turned points projecting toward the middle line of the handle.

What I claim, and desire to secure by Letters Patent, is—

The design for spoons, forks, and similar 55 articles consisting of the ornamental configuration on the front of the handle, substantially as shown.

RICHARD N. OAKMAN, JR.
